(57) **CLAIM**

The ornamental design of the solar spot light, as shown and described.

DESCRIPTION

FIG. 1 is a right side elevational view of the solar spot light in accordance with the present invention;

FIG. 2 is an elevational view of the front side of the solar spot light of the present invention;

FIG. 3 is a left side elevational view of the solar spot light of the present invention;

FIG. 4 is an elevational view of the rear of the solar spot light of the present invention;

FIG. 5 is a plan view illustrating the bottom surface of the solar spot light of the present invention;

FIG. 6 is a plan view illustrating the top surface of the solar spot light of the present invention;

FIG. 7 is a perspective view of the right side of the solar spot light in accordance with the present invention;

FIG. 8 is a perspective view of the left side of the solar spot light of the present invention; and,

FIG. 9 is a perspective view of the solar spot light of the present invention in use with and attached to a solar panel. The broken lines shown on the drawings are for illustrative purposes only and form no part of the claimed design.
